UNITED STATES PATENT OFFICE.

ARTHUR CAHN AND JACOB CAHN, OF NEW YORK, N. Y.

INDICATOR-MARKER FOR FILING-CABINETS.

1,031,321.

Specification of Letters Patent.

Patented July 2, 1912.

Application filed April 7, 1911. Serial No. 619,584.

To all whom it may concern:

Be it known that we, ARTHUR CAHN and JACOB CAHN, citizens of the United States, and residents of the borough of Bronx, in 5 the city and State of New York, have invented a new and useful Indicator-Marker for Filing-Cabinets, of which the following is a specification.

This invention relates to an indicator 10 marker for filing cabinets with the object in view of providing a device of this character which is adapted to mechanically indicate and hold the place from which a card or similar article contained in a drawer of a 15 filing cabinet has been removed.

Another object is to provide a device of 20 this character which is adapted to be manually thrown into and out of engagement with any card throughout the whole length of the drawer, and which will quite firmly hold its position against slipping far down between the cards and against longitudinal movement with respect to the drawer when in use.

A further object is to provide a device of 25 this character which will maintain a considerable separation between the cards at the place where the card has been removed in order that the cards may be readily separated at this point by the fingers when it is 30 desired to replace or read a card.

A further object is to provide certain improvements in the form, construction and arrangement of the various parts whereby the above-mentioned and other objects in- 35 herent in the device may be effectively carried out.

In the accompanying drawings, Figure 1 represents a top plan view of a filing cabinet drawer showing two of the indicator markers in operative position, Fig. 2 represents a top plan view, partly broken away, of a double drawer showing a pair of the indicator markers in use, one in each row of cards contained in the drawer, Fig. 3 represents a vertical section taken in the plane of the line A—A of Fig. 1, looking in the direction of the arrows, Fig. 4 represents a section taken in the plane of the line B—B of Fig. 2, looking in the direction of the arrows, Fig. 5 represents a detail longitudinal section of the indicator marker on its rod, Fig. 6 represents a detail transverse section through the indicator marker, taken in the plane of the line C—C of Fig. 5, looking in the direction of the arrows, Fig. 7 represents a longitudinal section taken in the plane of the line D—D of Fig. 1, looking in the direction of the arrows, Fig. 8 represents a top plan view, partly broken away, of a double drawer showing a modified form of indicator marker, Fig. 9 represents a transverse section taken in the plane of the line E—E of Fig. 8, looking in the direction of the arrows, Fig. 10 represents a detail longitudinal section through the modified form of indicator marker and its rod, and Fig. 11 represents a transverse section through the indicator marker taken in the plane of the line F—F of Fig. 10, looking in the direction of the arrows.

Referring to the form shown in Figs. 1 to 7, inclusive, part of the filing cabinet is represented by 1 and single and double drawers by 2 and 3, respectively. Rods 4 are mounted longitudinally of the drawers 2 and 3, and at one side of the single drawer 2 and centrally with respect to the double drawer 3. The manner of securing these rods in place is shown clearly in Fig. 7, the forward end of the rod being screwed into 75 the face of the drawer, as at 5, and the rear end of the rods 4 being provided with shoulders 6 fitted to rest on the top of the back of the drawer for holding the rod against depression; and the lower portion of the rear 80 end of the rod being provided with spikes 7 for holding the rod against vertical movement; while a screw 8 is further provided for securely holding the rear end of the rod in engagement with the back of the drawer. 85 Any convenient number of indicator markers may be provided as desired, but, in the present case, two are shown. These indicator markers are denoted by 9 and are provided with elongated hubs 10 pivotally 95 mounted on the rods 4 so as to permit the indicator markers 9 to swing at right angles to the rods 4 and also to slide longitudinally on the said rods. The indicator markers are longitudinally bent as shown in Fig. 5 100 and are provided with points or pricks 11 adapted to engage the cards in the drawer for the purpose of preventing the indicator marker from slipping on the surface of the card, and hence falling below a horizontal 105 position or moving upwardly off of the card when it is in use. The hub 10 is provided with a slot 12 at the rear side thereof for permitting the indicator to be manually moved longitudinally of the rod 4 when desired without undue friction. A thumb piece 13 is provided for convenient manipu-

2
lateral of the indicator marker. Each indicator marker is preferably provided with a pair of pricks 11 in order that it may be used in connection with a drawer containing a double row of cards, such as shown in Fig. 2, when occasion arises. In operation, still referring to the form shown in Figs. 1 to 7 inclusive; whenever occasion arises to remove a card from the drawers or to hold a place open between two cards without removing one, the cards may be separated at the point desired and the indicator marker swung down until its lower prick 11 engages the card at the rear of the separation between the row of cards. After the indicator marker is thus in engagement with the card, the hub of the said marker is given a slight push toward the rear. This movement forces the indicator marker slightly out of a right angular position with respect to the rod on which it is mounted, and causes the inner front portion of the elongated hub and the outer rear portion of the said hub to bind against the rod, and hence hold the marker against accidental longitudinal movement on its rod. The fact that the indicator marker is bent so that only the outer end engages the card causes this binding effect to be maintained. The prick 11 engaging the card, as described, prevents the end of the indicator marker from slipping either up or down on the card (which is generally at an abrupt slant, as shown,) while the hub is being cramped and after it is cramped. The indicator marker may then be left to denote the place from which the card has been removed or the place to which immediate access may be desired in the future; and the indicator will not only firmly hold this position but by reason of the fact that it is curved in cross section for forming the pricks 11 it will maintain a considerable separation between the cards at the point where it is applied, thus facilitating the re-insertion of the removed card or the reading of a card without removing it.

Referring to the form shown in Figs. 8 to 11 inclusive; the rod on which the indicator markers are mounted is supported in a channel or trough 14, the ends of which are secured to the front and rear of the drawer by means of screws 15. The sides of this channel 14 are of such a height with respect to the mounting of the rod 16 that the indicator marker 17 will engage the top of the trough 14, when the former is in its horizontal position, as shown in Fig. 9; thus absolutely preventing the indicator marker 17 from falling below a horizontal position. This indicator marker 17 is provided with a pair of pricks 18 quite similar in structure, and for exactly the same purpose as those above described in connection with Figs. 1 to 7 inclusive. Each indicator marker 17 is mounted on the rods 16 to swing in a man-

ner identical with the preferred form, and its head is provided with a spur 19 for providing a cramping engagement under the same conditions as that provided by the elongated hub 10 above described. The hole through the hub of the indicator marker 17 is flared toward the rear, as clearly shown at 20, in Fig. 10, for the purpose of permitting free manual longitudinal movement on the rod 16. The operation of this form of indicator marker is the same as that described in connection with the preferred form shown in Figs. 1 to 7 inclusive, and will not be repeated.

One type only of filing cabinet drawers has been shown, but it is clear that the invention herein described is equally applicable to any kind of filing cabinet drawer containing cards or the like. It will also be understood that various changes may be made in the form, construction and arrangement of the several parts without departing from the spirit and scope of our invention; hence we do not wish to be limited to the forms herein shown and described, but

What we claim is:-

1. In combination with a drawer for holding cards, an indicator fitted to swing into engagement with a card for separating it from an adjacent card, the said indicator being provided with means for preventing it from slipping on the card it engages.
2. In combination with a drawer for holding cards, an indicator fitted to swing into engagement with a card for separating it from an adjacent card, said indicator being provided with a prick for preventing it from slipping on the card it engages.
3. In combination with a drawer for holding cards, a rod mounted longitudinally thereof, and an indicator pivoted on said rod and fitted to swing into engagement with a card for separating it from an adjacent card, the said indicator having an elongated hub for cramping the rod, as the indicator is forced out of a right angular position with respect to the rod, for preventing the accidental longitudinal movement of the indicator on the rod when in use, the said hub being provided with an axially extending slot open at one edge of the hub for permitting free manual movement longitudinally of the rod when the free end portion of the indicator is not in engagement with a card.
4. In combination with a drawer for holding a double row of cards, an indicator mounted between said rows and fitted to swing into engagement with a card of either row for separating it from an adjacent card in the same row, the said indicator being provided with means for preventing it from slipping on the card it engages.

5. In combination with a drawer for holding cards, an indicator fitted to swing into

engagement with a card for separating it from an adjacent card, the said indicator being so bent that only its outer end engages the card when in operative position.

6. In combination with a drawer for holding cards, an indicator fitted to swing into engagement with a card for separating it from an adjacent card, the said indicator being so bent that only its free end portion 10 engages the card when in its operative position, and also further provided with means

for preventing it from slipping on the card it engages.

In testimony, that we claim the foregoing as our invention, we have signed our names 15 in presence of two witnesses, this sixth day of April 1911.

ARTHUR CAHN.
JACOB CAHN.
